United States Patent Office.

W. EDGAR SIMONDS, OF HARTFORD, CONNECTICUT.

Letters Patent No. 71,418, dated November 26, 1867.

IMPROVEMENT IN TELEGRAPH-INSULATORS.

The Schedule referred to in these Letters Patent and making part of the same.

TO ALL WHOM IT MAY CONCERN:

Be it known that I, W. E. SIMONDS, of Hartford, in the county of Hartford, and State of Connecticut, have invented a new and useful Improvement in Telegraph-Wire Insulator; and I do hereby declare that the following is a full, clear, and exact description thereof, which will enable those skilled in the art to make and use the same, reference being had to the accompanying drawings, forming part of this specification, in which—

Figure 1 is a central vertical section of my improved telegraph-wire insulator.

Figure 2 is a detached view of the cap or insulated portion of the device.

Similar letters of reference indicate corresponding parts.

This invention relates to an improvement in the construction of insulators for telegraph-wires, and consists in forming the glass, flint, or other insulated portion of the device, independent of the peg by which it is connected with the post for supporting the wires, and so arranged, in connection therewith, that rain or the moisture of condensation shall not settle around the base of the insulator and furnish a medium for the escape of electricity from the wire to the ground.

By my improved arrangement, a dry ring is preserved around the base of the insulator, which effectually prevents the escape of electricity.

A is a peg, made of wood or iron, for connection with a post or other fixture, for supporting a telegraph-wire, the upper end of which, *a*, is placed in a vertical position, and fits in the socket of a cap, B, made of glass, flint, or other non-conducting substance, to hold it in place. The insulator B is provided with a groove, *b*, around the knob at the end, for attaching the wire to it in the ordinary way, as shown in fig. 2. The base or lower part of the insulator B is formed like the hub of a wheel on the peg *a*, and having a flange or rim, *c*, projecting from it all around, and curving downward, so as to hang over and enclose an interior cup, *d*, that surrounds and may form a part of the supporting-peg A, when made of iron, or may be made separately, as a collar, around it, when the peg is made of wood. The inner base of the insulator B has a shoulder, *e*, around it, which sets low down in the cup *d*, and has a thin sheet of India rubber or rubber cloth, *g*, or other flexible, non-conducting material, lapped around it, like a thimble or hood, to be secured thereon by its own contraction, which rubber cover, *g*, descends nearly to the bottom of the cup *d*.

It will be seen that the inverted lip *c* of the insulator B projects over the upper edge of the lip of the cup *d*, and protects the base of the insulator from rain or descending moisture, while the lip of the cup *d* protects it from lateral or ascending moisture. It will further be protected by the India-rubber thimble or hood *g*, so that the space under it, and below the base of the insulator B, will be dry, and make its insulation on the peg A perfect.

Having described my invention, I claim as new, and desire to secure by Letters Patent—

The insulator B, having the inverted lip *c*, in combination with the cup *d*, the India-rubber hood *g*, and the supporting-peg A, constructed and arranged substantially as described.

W. EDGAR SIMONDS.
